CEMENT GROUT MIXING MACHINE

George Wentworth Grayson, Darling Point, near Sydney, Australia, assignor of one-fourth to Ronald Butler Hinder, Lindfield, near Sydney, Australia, one-fourth to John Thomas McKee, Sydney, Australia, and one-fourth to Edmund Percival Weber, Turramuna, near Sydney, Australia

Application October 20, 1932, Serial No. 638,756
In Australia October 31, 1931

2 Claims. (Cl. 83—73)

This invention relates to cement grout mixing machines of the type having on a suitable framing or chassis a proportioning mill constituted of a hopper or bin divided into a plurality of compartments (say two, one for cement and the other for sand) by division walls and having sloping side walls to discharge orifices adjacent each other and having revolvable radial vanes (the spaces between which constitute receptacles) on spindles in the hopper discharge orifices to apportion the ingredients from each hopper to mixing and distributing apparatus. The apportioning of the discharge from the several compartments in relation to each other as for example the cement and sand in such machines has hitherto been effected by the insertion of proportion plates between the vanes thereby reducing the volumetric capacity of the mentioned receptacles and practice has shown that such proportioning mechanism is not as effective as the mixing of cement grout requires. It is essential in the mixing of water cement sand and other materials as may be required for a grout that the quantities of each and particularly the cement and sand be maintained strictly in predetermined proportions. The mechanism used heretofore for this purpose delivers the several ingredients in the predetermined proportions only so long as the weight per unit volume of the ingredients—particularly the sand—remain constant. In practice the weight per unit volume of the sand varies considerably as for instance according to the moisture content or aeration thereof and the machine requires altering for every appreciable variation. This entails stopping the machine and fitting other proportion plates and again working the machine and testing the mix and so on working by trial and error until the correct mix is attained. The material and time wasted during this process of testing is obviously considerable and if such test material is used it may be so weakened as to seriously impair the strength of the ultimate structure.

It is only after the work has been completed that certain sections of the structure would show signs of failing under service conditions and these failings will in all probability be in sections coinciding with change in weight per unit volume of sand which change would almost invariably have been caused by weather or such other circumstances as would vary its moisture or air content.

Tests of the output from a machine of the type defined gave a variation on different days of the proportion from those to which the machine was

set for job dry materials (i. e. one part cement to two and one half parts sand (1-2½) by volume) of as much as from 1-1½ to 1 to 4; this was due in this case to weather conditions altering the moisture content of the sand and rendering it dry at one period and comparatively wet at another.

Like the proportioning apparatus the agitating and distributing apparatus on machines hitherto used has not been as effective as is desirable. It is necessary that the distributor convey the pre-mixed grout from the mixing apparatus to the point of application in an even and constant flow and in a state of continuous agitation to prevent segregation of the grout constituents and that the time taken in so conveying it (till deposited in a mass of broken metal as in a road bed) be maintained as predetermined to enable complete colloidal union of the grout constituents.

While machines hitherto have provided for the continuous agitation of the grout they have not provided readily adjustable mechanism to ensure an even and constant flow of the mix and the maintenance of a predetermined duration of time to convey said mix along the distributor.

The disability has been due in a large measure to the fact that it has not been practicable to keep the angle of inclination of the distributor in relation to the horizontal constant when in use. For example when the machine is working on an incline as on a road it has not been practicable with mechanism hitherto available to swing the distributor from one extreme position to the other that is through an angle of 180° without varying such angle of inclination.

Now this invention has been devised to overcome the stated difficulties by providing simple mechanism which will enable say an intelligent foreman or like workman to carry out the supervision and correction of the variations of a cement and sand mix and to maintain an even and constant flow of it as part of his general duties while the machine is running and this without any interruption to the continuity of the working of the machine.

In order that the invention may be readily carried into practical effect it will now be described with reference to the drawings accompanying and forming part of this complete specification. Fig. 1 is a schematic side elevation of a cement grout mixing machine embodying these present improvements; Fig. 2 is a plan thereof; Fig. 3 is a diagrammatic layout of proportioning mill driving gears; Fig. 4 is a part sectional elevation of a proportioning mill, and Fig. 5 is a section on line

5—5 Fig. 1, while Fig. 6 is a fragmentary end elevation thereof.

The machine is constituted of a wheeled chassis 5 with or without ordinary steering mechanism and propelling mechanism (not shown). A prime motor 6 and proportioning mill 7 are mounted on the chassis 5. One end of a mixing trough 8 is juxtaposed below said mill and at its other end said trough has a universal union or discharge 9 to a distributor 10 having outlet 11 with spreading chute 12. The prime motor 6 has a drive through intermediate gears to shaft 13 and said shaft 13 preferably has a take off 14 to a machine propelling mechanism not shown. Pinion 15 on said shaft 13 drives through intermediate gear 16 mill-gears 17 and 18 and agitator-gears 19 and 20 and said shaft 13 is coupled to or is integral with shaft 21 within the mixing trough 8. This shaft 21 extends the full length of the mixing trough 8 having suitable bearings in the ends thereof and has helically set mixing paddles 22 mounted thereon and on the rear end has a bevel pinion 23 within universal coupling 24 meshing a crown wheel 25 which meshes a bevel pinion 26 on telescopic shaft 27 which through gearing 28 operates helically set paddle conveyor 29 in the distributor 10. Clutches to operate the several drives are incorporated as well understood. Slipping clutches are also incorporated as well understood to prevent breakage of the working parts in case of a jam in the materials.

The proportioning mill (Figs. 3, 4, 5 and 6) is constituted of end walls 30 and 31 having at top hoppers 32 and 33 (for cement and sand) wherein are agitators 34 and 35 rotated by gears 19 and 20 respectively. Across the hopper discharge orifices are shafts 36 and 37 (in suitable end bearings) whereon are mounted sets of vanes 38 and 39 (the spaces between which constitute allocating receptacles) keyed to or integral with shafts 36 and 37 which are rotated by gears 17 and 18. The shafts 36 and 37 and also the shaft 21 are each provided with deflector discs 40 which prevent any cement or sand lodging in their respective bearings.

On the hoppers 32 and 33 are sealing and guiding plates 41 and 42 hinged at their top edges as at 43 and adapted to be firmly pressed against the peripheral edges of the vanes 38 and 39 by compression springs 44 on the ends of arms 45 affixed to said plates 41 and 42. These plates are incorporated to prevent the cement or sand discharging other than from the vanes receptacles and the springs 44 permit of large size particles as stones to pass between vanes and plates 41 and 42 without fracturing said plates.

Mounted on the shafts 36 and 37 are longitudinally reciprocatable proportioning cylinders 46 and 47 adapted to partly occlude the apertures of the allocating receptacles and said cylinders are of approximately the same diameter as the vanes 38 and 39 and have longitudinal slots 48 wherein said vanes are adapted to slide home as said proportioning cylinders are advanced across the mouth of the hoppers. These cylinders 46 and 47 have at one end bearings 49 slideable on the shafts 36 and 37 and have at their other ends quadrant supports 50 adapted to slidably fit between the vanes 38 and 39. The proportioning cylinders 46 and 47 have end collars 51 having shifting dogs 52 in grooves thereon said dogs having integral carrier nuts 53 on screwed spindles 54 in end bearings 55 and 56. The nuts 53 have pointers 57 thereon juxtaposed a scale 58 graduated say in tenths and hundredths and the spindles 54 are provided with turning wheels 59.

The spindles 38 and 39 have vibrators at the outer ends thereof comprised of cup cam 60 engaging a spur 61 on a plate 62 having a hammer 63 thereon said plate being fast to a lever 64 hinged on pin 65 in bearings 66 on the trough 8 said spur being spring held against the cams 60 by tension spring 67.

The distributor 10 is supported by stays 68 and 75 the latter having tension springs 69 interposed therein. The lower end of the stay 75 is hinged to bracket 70 and has its top end 71 screwed and passing freely through a trunnion 72 and is provided with wheel nut 73. The trunnion 72 is freely rotatable in the top of a post 74 and said trunnion is compelled to rotate with the distributor 10 by said stay 75. The post 74 is bifurcated at bottom and is hinged in bearings 76 and its position is adjustable by stay 77 which is comprised of a screw 78 (having turn wheel 79) homing within a nut 80 on a divergent stay rod 81 pivoted in bearings 82 one on either side of the chassis 8.

A water supply for the making of the grout comprises a tank 83 having a float operated inlet valve and having outlet pipe 84 with regulating valve 85 thereon and having delivery nozzle 86 directed into the mixing trough 8 at about the position shown.

It is to be clearly understood that though the cement and sand allocators are both described as having proportioning mechanism incorporated therewith the machine may be effectively operated with such mechanism on the sand allocator only. Further though the machine has been described as having cement and sand proportioning mechanism only it may well have proportioning mechanism for such other ingredients that it may be desired to incorporate in the grout.

In use the distributor 10 is first set at the required angle of inclination by operation of the wheels 71 and 79 but the post 74 must be vertical to allow distributor 10 to always maintain a constant angle with the vertical. The machine driving mechanism is set in motion and cement and sand is fed into the hoppers other materials being added as required or other hoppers incorporated in the machine therefore. For the production of an effective grout the sand should be of such fineness that it will all pass through a fine mesh sieve, say 30 mesh, or if coarse sand is used it should be amalgamated with some fine material as fine sands or a diatomaceous earth or hydrated lime so that colloidal union of the ingredients is facilitated. The proportioning cylinders are positioned on the vanes so that only the required proportions of cement and sand (and other material required) may pass through said hoppers. The manipulation of said cylinders will be more fully described later herein. The agitators 34—35 keep the cement sand and other admixture moving downward toward the apportioning mechanism and will cause the receptacles to be filled effectively but the surface tension between moist particles of sand and between moist sand and metal if used may be sufficient to bulk the sand together and hold it in the proportioning mechanism so preventing complete discharge of apportioned material to the mixing and distributing apparatus, at the speed of rotation of the proportioning mechanism.

To enable complete discharge of apportioned

materials under all conditions however induced—vibratory mechanism—in this case hammers 63 strike spindles 36 and 37 thereby causing the vanes 38—39 to vibrate with sufficient intensity to completely discharge the apportioned material.

5 The number of vibratory blows administered to the vanes per revolution thereof should at least be equal to the number of proportioning receptacles and the striking should preferably coincide with the position of the receptacle at which maximum discharge takes place.

10 The water is turned on and by reason of the constant level thereof in the tank maintained by the float operated valve the flow thereof from the 15 nozzles 86 is uniform.

15 The apportioned materials and water pass from respective hoppers and tank into the mixing trough 8 where the revolving mixing paddles thoroughly amalgamate the ingredients and travel the 20 mix along to the discharge 9. The now formed cement grout passes through the discharge 9 to the distributor 10 which is adjusted so that it may be operated to the full extent of its radial travel on the same horizontal plane irrespective 25 of the angle of inclination of the machine. This is effected by adjusting the length of the stay 81 to position the post 74 vertical. Having the distributor 10 adjusted as before stated an even and 30 constant flow of the mix is maintained while the paddles of the conveyor 29 keep the mix in a state of continuous agitation and prevents segregation of the ingredients. The angle of inclination of the distributor 10 being constant the mix is conveyed therealong mechanically and the time 35 taken is in accordance with a predetermined speed of the revolution of the conveyor and is sufficient to insure complete colloidal union of the grout constituents.

40 The proportions of cement and sand are controlled under field conditions in the following manner. For example say the specification demands the proportions of one cement to two and one half of sand in a dry condition (1—2½) the pointer on the cement shutter screw is set to read 45 30 on the scale and the position of the pointer on the sand shutter screw should then be adjusted to read $30 \times 2\frac{1}{2} = 75$ on the scale. If the sand was absolutely dry that is devoid of any moisture content (which is very rare in practical conditions) the mix would be one cement to two and one half sand as per specification but as a very small moisture content increases the sand bulk a correction will have to be made to one of the settings as hereinafter described.

50 It is known that sand increases in bulk when moist but when completely inundated resumes its dry volume that is practically the same volume as when oven dried. A measuring glass preferably about 10 or 12 inches in length and one to two and 55 a half inches in diameter graduated into tenths and hundredths is filled up to say the 50 mark and the sand to be used and then filled with water. The glass is thoroughly shaken and then placed in a stationary upright position to allow the sand to settle in the water. The sand will settle back to a mark which would have been its position had it been dry when first put into the glass. The difference between the two readings shows the difference in bulk due to moisture content and the inundated readings divided by the first reading (viz. 50) multiplied by 100 will give the percentage increase of bulk due to moisture content and therefore the pointer on the sand scale will have to be moved to counteract the effect of bulk- 60 ing as in following example correction:—

After settling the reading at the top of the sand (inundated) is say 40 so that the percentage difference of the sand in bulk or volume due to moisture content is

$$[(\frac{50}{40})-1] \times 100 = 25\%$$

that is the total bulk or volume of sand passing through the sand allocator is 25% less than that desired and this is due to moisture content. 10 Therefore the reading on the sand scale will have to be increased as follows. The sand scale reading 15 75 will have to be increased 25% to make allowance for the moisture content in the sand and the correction to the reading (that is the new 20 reading) will be

$$(\frac{75 \times 25}{100}) + 75 = 93.75.$$

The proportioning of the mill will now be correct 20 the scales now reading 30 cement and 94 sand.

25 A check of the proportions of the grout as mixed should be taken as delivered from the machine on to the road after the manner of the example below and after settling the sand will go to the bottom and the cement to the top the line between the two being sharp and clearly defined. This is due to the difference in the specific gravities of sand and cement therefore the reading at the top of the sand that is the line dividing 30 the sand and cement gives the quantity of sand in the glass and the same reading subtracted from the top reading (the reading at the top of the cement) will give the quantity of cement in the glass and the one divided into the other will give 35 the ratio of proportions.

40 For example fill the glass up to the 50 mark with grout and fill with water. Shake thoroughly and allow to settle as before stated. If the grout proportions were correct viz. 1 cement to $2\frac{1}{2}$ of sand ($1-2\frac{1}{2}$) specification then the reading of 45 the glass at the top of the sand should be

$$(\frac{50}{1-2\frac{1}{2}}) \times 2\frac{1}{2} = 35.715$$

50 this being the amount of sand and this reading 45 subtracted from 50 should equal

$$(\frac{50}{1+2\frac{1}{2}}) = 14.285$$

55 showing the amount of cement so that 35.715 divided by 14.285 = $2\frac{1}{2}$ which are the correct proportions viz. one part of cement to two and one half sand.

Now suppose that the test of the proportions of the grout disclosed that the proportions were 55 not correct and the glass readings were top 50 and at the division between cement and sand 34 so the quantity of cement = $50 - 34 = 16$ and the sand quantity is 34 then the proportion ratio is 34 divided by 16 = 2.122 that is one part cement 60 to 2.122 parts of sand instead of $1-2\frac{1}{2}$; therefore the mix is richer than the specification calls for by

$$[(\frac{2\frac{1}{2}}{2.122})-1] \times 100 = 17.79\%.$$

65 The reading on the cement scale should therefore be reduced say 18%. The reading 30 opposite the cement pointer will have to be reduced 18%, viz. to

$$30 - (\frac{30 \times 18}{100}) = 24.60$$

70 so changing the settings on the machine they now read 24.60 to the cement pointer and the sand pointer remaining unchanged viz. 94.

Again suppose that the test of the proportions of the grout test disclosed too lean a mixture the glass readings being top 50 and at the division between the cement and sand 38 then the quantity of cement = 50 - 38 = 12 the sand quantity being that reading dividing sand and cement viz. 38 the proportions are 38 divided by 12 = 3.166 that is one of cement to 3.166 sand so the mix is too lean in cement by

10
$$\left[\left(\frac{3.166}{2\frac{1}{2}} \right) - 1 \right] \times 100 = 26.7\%$$

this being so the reading 30 opposite the cement pointer will have to be increased by 26.7% viz.

15
$$30 + \left(\frac{30 \times 26.7}{100} \right) = 38$$

so that the settings on the machine now read 38 for the cement pointer and the sand pointer remains unchanged viz. 94.

20 I claim:—

1. In a cement mixing machine the combination including a distributing channel, a shaft rotatably mounted within the distributing channel, a plurality of helically arranged agitating and conveying blades on the shaft within the distributing channel, means for maintaining a particular inclination of the agitating and distributing channel including a post hinged at one end to the machine and mounted in the same vertical axis as the axis of radiation of the distributing channel, a swivel head on the post, an adjustable guy extending from the post supporting said distributing channel, means for maintaining the swivel head in alignment with the supporting guy, an adjustable stay hinged to the machine and the said post, and means to rotate the agitator in the channel.

2. In a cement mixing machine, the combination including a proportioning mill comprising a hopper for sand and a hopper for cement, a rotatably mounted agitator within each of the hoppers, a discharge below each hopper, rotatably mounted veins in the orifice of the discharge of each hopper, a fixed shaft mounted outside of each hopper, a shutter for each hopper slidably mounted on the fixed shaft associated therewith and the veins within the hopper, a threaded spindle for each shutter rotatably mounted parallel to the axis of the shutter, a traversing nut on each spindle, means for connecting the shutter and the traversing nut associated therewith, a graduated scale above the threaded spindle, a 15 vibrator timed to strike the shaft upon which the veins are mounted when each cavity between a pair of veins is open to the discharge of the hopper, a mixing channel disposed immediately below the discharge of said proportioning mill, 20 a shaft rotatably mounted within the channel, a plurality of helical mixing and conveying blades mounted on the shaft, an agitating and distributing channel, a swivel connection between said mixing channel and said agitating and distributing channel, means for maintaining a particular inclination of the agitating and distributing channel including a post hinged at one end to the machine and mounted in the same vertical axis as the axis of radiation of the distributing 25 channel, a swivel head on the post, an adjustable guide supporting said distributing channel, means for maintaining the swivel head in alignment with the supporting guide, and an adjustable stay hinged to the machine and the said post, means 30 to rotate the agitators in the channels and means for operating said vibrator.

GEORGE WENTWORTH GRAYSON.
